KEY HOLDER

Rene M. Schupbach, Providence, R. I., assignor
to Freeman-Daughaday Company, a corpora-
tion of Massachusetts

Application February 26, 1937, Serial No. 127,898

7 Claims. (CL. 70—459)

This invention relates to a key ring or key holder and has for one of its objects the provision of a simple device of this type which will be effectively held in closed or locked position to prevent escape of any keys which may be positioned thereon.

Another object of the invention is the provision of a key holder having a suspending loop for attachment to a chain, cord or other flexible member with an arrangement such that the parts will tend to move into locking position.

Another object of the invention is to provide an exceedingly thin construction in substantially a single plane in which there will be no bulging parts at the hinge joint, and thus one, the hinge joint of which will be inconspicuous.

Another object of the invention is to so arrange the moving parts that they will move into locked position without manual compression of the body of the ring.

With these and other objects in view the invention consists of certain novel features of construction, as will be more fully described, and particularly pointed out in the appended claims.

In the accompanying drawing:

Fig. 1 is a side elevation of the key holder;
Fig. 2 is a view similar to Fig. 1 but partly in section illustrating the structure of the closure member;

Fig. 3 is a view similar to Fig. 2 with the closure member moved to open position;
Fig. 4 is a perspective view of the body portion of the holder alone;

Fig. 5 is a perspective view of the closure member;

Fig. 6 is an edge view of the key holder showing its thin formation with the suspending loop in substantial plan.

Key holders or key rings of the type in which some portion is threaded through the opening in the handle end of the key are known and are of various constructions. In some structures where a suspending loop is provided, it either has no effect in the function of the device or serves to tend to open the closure member when tension is applied; and in order to provide a more effective closure member and one in which the suspending loop will function to draw the parts into closed position, I have provided that the closure member swing inwardly to open position and when swung outwardly to closed position it will engage the body, and I have so arranged the suspending loop that tension on the loop will move these parts into firm closed relationship; and the following is a more detailed description of the

present embodiment of this invention, illustrating the preferred means by which these advantageous results may be accomplished.

With reference to the drawing, 10 designates the body portion of the key ring or key holder which, as shown in Fig. 4, is disposed in a curved shape substantially along the arc of a circle although various other shapes may be utilized. This body is tapered from the end 11 at which the closure member 12 (see Fig. 5) is pivoted or hinged, to its end 13 which is provided with a hook 14 for effecting a holding of this end to the closure member. This taper provides more resiliency in the end portion where the hook is situated than in the hinged portion of the device which is found to be more desirable.

The closure member designated generally 12 has an enlarged head end 15 and narrower shank portion 16 which conforms to the width and general shape or configuration of the end portion 11 of the body and when hinged thereto its outer and inner surfaces are an extension of the outer and inner tapered surfaces of the body. The body is cut away as at 17 along one side surface and the closure member 16 is cut as at 18 along the opposite side surface so as to provide an overlapping connection with the opposite surfaces 19 and 20 of these overlapping portions substantially aligned with the adjacent surfaces 21 and 22 of the closure member so that this closure member aligns with the body not only on its inner and outer surfaces but also on both side surfaces. A pivot or hinge pin 23 serves to pivotally or hingedly connect the body and this closure member so that the closure member may be swung from position shown in Fig. 2 to the position shown in Fig. 3 about this hinged connection.

The head 15 of the closure member is not only of a larger dimension radially of the key holder but is also of a larger dimension laterally and is provided with a slot 25 of a sufficient size to receive the end portion 13 and hook 14 of the body. A pin 26 extends through the head and across the slot and the hook 14 of the body receives this pin in the hook shaped recess 27 as illustrated in Fig. 2. The distance from the hinge or pivot 23 to the pin 26 is less than the distance from the pin 23 to the inner edge 28 of the hook 14 when the body is normal or unrestrained, so that the ends of the body 10 of the key ring must be sprung toward each other in order for the hook to engage the pin 26 and when so engaged with the pin the body will be under tension tending to expand and will thus hold these parts firmly in engagement. The end of the hook 14 is so shaped as

at 30 that were the closure member 12 moved outwardly the pin 26 would contact this tip 30 along its inner surface 31 and be guided into the hook.

5 It will be apparent from what has been heretofore said that the member 12 is in open position in Fig. 3 and may be swung from the position in Fig. 3 to the closed position shown in Fig. 2 by flexing the body so that the pin 26 may be engaged by the hook and that for opening movement a reversal of this operation must occur. Also it will be apparent that the swinging outwardly of the closure member is blocked by an engagement with the body so that the 10 closure member may never swing outwardly beyond the body in the plane of the body, the parts 15 all being normally located and disposed in a single plane.

It is desirable that some suspending means be 20 provided for the key holder, and to accomplish this I have provided a loop 29 pivoted as at 30 to the closure member in the opening 31 through the closure member, this loop being in the form of a horseshoe with its ends 32 extending into 25 the opening 31. This opening 31 is located between the end of the closure member and the hinge 23 and at a substantial distance from the hinge, a convenient location is about in the middle of the closure member. Thus, if any tension 30 is placed on this loop as would be the case were the same suspended on a chain with keys on the body diametrically opposite the closure, the tendency would be for the closure member to be moved outwardly about its hinge or pivot 23 35 so as to move this closure member more firmly into engagement with the end of the body or the hook that a firmer engagement may be had rather than any tendency to move the closure member to open position.

40 The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A key ring or key holder comprising a curved resilient body with its ends spaced, a member 50 hinged to one end of said body and swingable inwardly of the body to open position and outwardly into engagement with the body to closed position, and an attaching loop carried by said member at a point spaced from said hinge to be 55 engaged by a suspending chain whereby outward tension on said loop serves to move said member into firmer closed position.

2. A key ring or key holder comprising a curved resilient body in substantially a single plane with 60 its ends spaced, a member hinged to one end of said body and swingable inwardly in the said plane of the body to open position and outwardly into engagement with the body to closed position and an attaching loop carried by said member at a point spaced from said hinge to be 65 engaged by a suspending chain whereby outward

tension on said loop serves to move said member into firmer closed position.

3. A key ring or key holder comprising a curved resilient body with its ends spaced, a member hinged to one end of said body and swingable 5 inwardly of the body to open position and outwardly into engagement with the body to closed position, means comprising an interlocking connection between said member and body, and an attaching loop carried by said member to be 10 engaged by a suspending chain whereby outward tension on said loop serves to move said member into firmer closed position.

4. A key ring or key holder comprising a curved resilient body with its ends spaced, a member 15 hinged to one end of said body and swingable inwardly of the body to open position and outwardly into engagement with the body to closed position, said member being slotted and provided with a pin extending between the walls of said 20 slot and said body having an inwardly curved hook end to fit in said slot and be guided thereby over said pin, and an attaching loop carried by said member to be engaged by a suspending chain whereby outward tension on said loop serves to 25 move said member into firm closed position.

5. A key ring or key holder comprising an arcuate, curved resilient body in substantially a single plane with its ends spaced, a member hinged to one end of said body and swingable 30 inwardly in the said plane of the body to open position and outwardly into engagement with the body to closed position, said member being slotted and provided with a pin extending between the walls of said slot and said body having an inwardly curved hook end to fit in said slot and be guided thereby over said pin the distance between said pin and hinge connection being less than the unrestrained distance between said hinge connection and hook end whereby the 40 ends of the body must be moved toward each other for locking of the member in closed position to place the body under an inherent tendency to expand.

6. A key ring or key holder comprising a curved 45 resilient body with its ends spaced, a member hinged to one end of said body and swingable inwardly of the body to open position and outwardly into engagement with the body to closed position, said member being slotted and provided 50 with a pin extending between the walls of said slot and said body having an inwardly curved hook end to fit in said slot and over said pin, and means on said hook end to guide the pin into engagement with the hook upon movement toward closed position.

7. A key ring or key holder comprising a curved resilient body with its ends spaced, a member hinged to one end of said body and swingable 60 inwardly of the body to open position and outwardly into engagement with the body to closed position, said member being slotted and provided with a pin extending between the walls of said slot and said body having an inwardly curved hook end to fit in said slot and over said pin.
